(57) **CLAIM**

The ornamental design for a dispenser for personal care liquids, as shown and described.

DESCRIPTION

FIG. 1 is a front perspective view of a dispenser for personal care liquids.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof.

FIG. 7 is a right side elevational view thereof; and, FIG. 8 is a front perspective view of the dispenser of FIG. 1 in a position of use as secured to a tiled wall.

The structures and features shown in broken lines in FIGS. 1-8 form no part of the claimed design.

1 Claim, 5 Drawing Sheets(56)
